Patented Nov. 12, 1974

233,580

STRAND OF BEADS FOR A CURTAIN ELEMENT OR THE LIKE

Irving Levine, 5212 Weller Drive,
Woodland Hills, Calif. 91364

Filed Oct. 30, 1969, Ser. No. 19,843

Term of patent 14 years

The term of this patent subsequent to Apr. 12, 1984,
has been disclaimed

Int. Cl. D6—10
U.S. Cl. D6—205

FIG. 1

FIG. 3

FIG. 2

FIG. 1 is a side elevation view of a strand of beads for a curtain element or the like showing my new design in which two repeat units are illustrated;

FIG. 2 is an end view of a portion of said strand taken along line 2—2 of FIG. 1; and

FIG. 3 is an end view of a portion of said strand taken along line 3—3 of FIG. 1.

I claim:

The ornamental design of a strand of beads for a curtain element or the like, substantially as shown.
